UNITED STATES PATENT OFFICE.

JOSEPH DERK, OF PHILADELPHIA, PENNSYLVANIA.

DESIGN FOR A TABLE SCARF.

Application filed December 10, 1924. Serial No. 11,650. Term of patent 3½ years.

To all whom it may concern:

Be it known that I, JOSEPH DERK, a citizen of the United States, residing in the city and county of Philadelphia, State of Pennsylvania, have invented a new, original, and ornamental Design for a Table Scarf, of which the following is a specification, reference being had to the accompanying drawing, forming part thereof.

The figure is a plan view of a portion of a table scarf, showing my new design, said portion being duplicated at the opposite end thereof.

I claim:

The ornamental design for a table scarf, as shown.

JOSEPH DERK.
